UNITED STATES PATENT OFFICE.

EARL L. PRICE, OF OAKLAND, CALIFORNIA.

CAN-DRAINING MACHINE.

Application filed November 9, 1921. Serial No. 513,920.

To all whom it may concern:

Be it known that I, EARL L. PRICE, a citizen of the United States, residing at Oakland, in the county of Alameda and State of California, have invented new and useful Improvements in Can-Draining Machines, of which the following is a specification.

This invention relates to a draining machine, and especially to a machine for inverting and draining packed cans containing washed, wet fruit and the like.

The fruit canning industry has today reached enormous proportions and competition between the many packing plants in operation has accordingly become comparatively keen. To insure a high grade marketable pack several problems must be considered; for instance uniformity in size of the fruit being packed is one factor; thorough washing of the fruit before packing in the cans is necessary to insure sanitation and appearance, and above all the sugar content of the syrup applied must be considered as this does not only affect the keeping qualities of the fruit, but also the taste thereof. For this reason it is not only desirable, but almost necessary, that the wash water adhering to the surface of the fruit be thoroughly drained off or removed before the syrup is applied, as any water remaining on the fruit or in the cans will naturally dilute the syrup and thereby vary the sugar content.

Machines for automatically receiving, inverting and draining the contents of cans are not broadly new, but most machines in use today are rather complicated in construction and have a limited draining period and capacity.

The object of the present invention is to generally improve and simplify machines of this character, and especially to increase the draining period to insure complete removal of the water content, and at the same time to materially increase the capacity of such machines, or in other words the number of cans handled per minute.

Further objects will hereinafter appear. The invention consists of the parts and the construction, combination and arrangement of parts as hereinafter more fully described and claimed, having reference to the accompanying drawings, in which—

Fig. 1 is a side elevation of the can draining machine.

Fig. 2 is a plan view of the same.

Fig. 3 is a plan section taken on line 3—3 Fig. 1.

Referring to the drawings in detail, and particularly to Figs. 1 and 2, A indicates in general a frame consisting of a pair of interspaced angle bars 2 and 3, supported with relation to a runway 4 by means of uprights or standards 5. Passing over the runway 4 is an endless can conveying sprocket chain 6, and secured thereon, at equally spaced intervals, are can feeding lugs 7. Disposed at each end of the frame A are journaled members 8, and turnably mounted in each set of journal members are shafts 9 on each of which is secured a pair of interspaced sprocket gears 10 and 11. Supported by each set of aligned sprocket gears 10 and 11 is an endless chain 12, and disposed between the chains are perforated plates 13. Formed integral with each plate is a T-shaped conveying arm 14, and secured to the frame A and disposed at each side of the conveying arms are side guiding bars 15 and an exterior guiding plate generally indicated at B. The guiding plate is secured at the lower end, as at 16, to one side of the runway 6. It is next extended horizontally, as at 17, to receive the cans indicated at 18. The plate is then bent to form a semi-circle as at 19, and it is again extended horizontally, as at 20, to form a connection with the opposite end 21, which is also semi-circular in shape. The plate finally terminates in a horizontal portion 22, which is attached to the opposite side of the runway 6, as at 23. In other words the plate B conforms to the path of travel assumed by the sprocket chains 12 and cans delivered by the runway 6 will therefore engage the perforated plates 13 and stay in engagement therewith during inversion of the cans as will hereinafter be described.

The spacing between the conveying arms 14 and the lugs 7 is equal. The linear speed of travel is also equal and for this reason it is obvious that a uniform speed must be maintained and that a common drive will be preferable. This driving connection is generally indicated at C. It consists of a pair of journal members 24 in which is turnably mounted a shaft 25. Secured on the shaft is a sprocket gear 26 which is disposed between the journal members 24, and also secured thereon is a bevel pinion gear 27 which intermeshes with a similar

pinion 28 secured on the shaft 9, which supports and drives the sprocket gears 11. The endless can conveying chain supported by the runway 6 is driven from the sprocket gear 26 by means of a chain 29, and a uniform speed is thus maintained; this being essential as the travel of the feeding lugs 7 with relation to the conveying arms 14 is of considerable importance. A pulley or 10 other driving connection, such as indicated at 30, may be employed to drive the mechanism as a whole. This may be mounted on one of the shafts supporting the endless chain conveyor 6 as here illustrated, or 15 otherwise disposed, as the location of the same is obviously only a matter of choice.

In actual operation cans packed with washed fruit are placed on the endless conveyor 6. As this is continuously moving, 20 cans will be delivered one by one to the cross conveyor consisting of the chains 12 and the conveyor arms 14. Each can entering will be removed by the arms 14 and will be carried first over the flat portion 17, and 25 then around and in under the curved portion 19; the cans assuming complete inverted position when passing under the upper portion 20. The spacing between the sprockets 10 and 11 is such that the cans 30 remain in the completely inverted position a sufficient length of time to insure perfect removal of any water which may adhere to the surface of the fruit, or which may otherwise have collected in the cans. For the 35 purpose of collecting such drain water and to prevent it from dripping down in the entering or discharging cans, a collecting pan 40 is employed. This pan is disposed directly below the chains 12 and is suitably 40 supported with relation to the main frame A; all drain water collected being discharged through a pipe 41, which delivers the water to a main collecting pan disposed below the machine as indicated at 42, that 45 is the cans are gradually inverted while passing around and in under the curved portion 19. This water drains downwardly through the mechanism and is caught by the pan 42. The main water content of the 50 cans is however removed during the complete inverted position assumed, and it is therefore caught by the pan 40 which overflows or discharges into the pan 42; the water being drained away from the pan 42 55 in any suitable manner or by means of a pipe 43. After the cans have travelled around the upper portion of the conveyor, it is again necessary to re-invert the cans. This is accomplished by passing them 60 around and in under the curved portion 21. They here gradually assume an upright position and are completely righted when the horizontal portion 22 is reached. The 65 cans being impelled or kept in constant movement during their entire travel with

the cross conveyor by the arms 14 will be returned to the main feeding conveyor 6, and they are therefore not only delivered to the draining portion of the mechanism by said conveyor, but also removed therefrom by said conveyor. To prevent interference of the entering and discharging cans, it is advisable to slightly advance the discharging cans with relation to the horizontal section 22; the advance movement 70 taking place in the direction of travel of the conveyor 6. This advance movement or lateral movement with relation to the plate 22 is caused by an angularly disposed side guide 44 which forms a terminating end of 80 the main side guide 15. During this advance movement imparted by the angularly disposed terminating end 44, each can will gradually travel with relation to the chain 6, or in other words be replaced thereupon, and when complete alignment is obtained one of the lugs 7 will reach a point of engagement and thereby remove the cans in successive order. In other words while one lug 7 is delivering a can, the lug in advance 85 thereof will travel into engagement with relation to a drained can and will remove the same. Similarly while one arm 14 engages an entering can to remove it with relation to the feeding conveyor, another arm 14 will be returning a drained can to the feed conveyor and the returning can will at the same time travel laterally with relation to said arm 14 to release itself with 90 relation thereto, as such movement is imparted by the guide member 44. When complete released position is assumed, a drained can will be re-deposited on the conveyor 6 and a lug 7 will engage and remove the same. 95

From the foregoing it can be seen that an exceedingly simple draining machine has been provided. A single ordinary endless chain conveyor is provided for the purpose of delivering and removing the cans, and a 100 similar ordinary endless chain conveyor disposed at right angles thereto serves the function of removing the cans, inverting the same, and returning the cans to the feed conveyor. By increasing or decreasing the spacing of the sprockets 10 and 11, any length of draining period desired can be obtained, and as this is possible, it is obvious that the capacity, or in other words the number of cans handled per minute, may be increased or decreased as desired. A fool-proof, simple mechanism is employed; perfect draining of the contents of the cans is secured, and any capacity desired may be obtained without interfering with the draining of the can contents. The mechanism shown is rather 110 specifically illustrated and for this reason merely shows one form of construction. The frame for instance consists of angle and strap iron, but may obviously consist of 115 120 125 130

frame castings or the like, if desired. I also wish it understood that various changes in form and proportion may be resorted to within the scope of the appended claims, 5 similarly that the materials and finish of the several parts employed may be such as the experience and judgment of the manufacturer may dictate or varying uses may demand.

10 Having thus described my invention, what I claim and desire to secure by Letters Patent is—

1. In a draining machine of the character described, a can conveyor, an endless conveyor disposed at right angles to the first conveyor and including a relatively long upper substantially horizontal stretch, said second conveyor being adapted to remove the cans from the first conveyor and redeliver 15 the cans to the first conveyor, and during removal and redelivery of the cans from and to the first conveyor, inverting a plurality of cans at a time on said relatively long horizontal stretch of the endless conveyor.
- 20 2. In a draining machine of the character described, a can conveyor, an endless conveyor disposed at right angles to the first conveyor and including a relatively long upper substantially horizontal stretch, a relatively long frame having rounded ends enclosing the second mentioned conveyor and

adapted to cooperate with the latter to guide the cans through the machine, said second conveyor being adapted to remove a can from the first conveyor and redeliver the can to the first conveyor and between the removal and redelivery of the can to the first conveyor carrying a plurality of cans at a time inverted across said stretch from end to end thereof.

3. In a draining machine of the character described, a can conveyor, an endless conveyor disposed at right angles to the first conveyor and including a relatively long upper substantially horizontal stretch, such second conveyor being adapted to remove a can from the first conveyor and redeliver the can to the first conveyor and between the removal and redelivery of the can to the first conveyor carrying a plurality of cans inverted across said stretch from end to end thereof, and means whereby to slightly deflect laterally the cross travel of the discharging can adjacent the first mentioned conveyor in the direction of travel of the latter, so as to slightly advance the discharging cans with relation to the entry cans and thereby prevent interference of the entry cans and discharge cans adjacent the point of entry and discharge to and from the second main 45 conveyor.
